(57) **CLAIM**

The ornamental design for a cooking appliance as shown and described.

DESCRIPTION

FIG. 1 is a perspective view of a cooking appliance shown with a door thereof in a closed position;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a perspective view of the cooking appliance shown with the door in an open position;
FIG. 9 is a front elevation view thereof;
FIG. 10 is a back elevation view thereof;
FIG. 11 is a right side elevation view thereof;
FIG. 12 is a left side elevation view thereof;
FIG. 13 is a top plan view thereof; and,
FIG. 14 is a bottom plan view thereof.

The even dashed broken lines show portions of the cooking appliance and form no part of the claimed design.

The dot-dash broken lines illustrate the bounds of the claimed design and form no part thereof.

Oblique shading is used to represent surfaces that are transparent.

1 Claim, 14 Drawing Sheets
